DOMESTIC APPLIANCE

Robert R. Cандor, Oakwood, Ohio, assignor to
General Motors Corporation, Dayton, Ohio, a
corporation of Delaware

Application January 30, 1948, Serial No. 5,320

5 Claims. (Cl. 68—21)

1

This invention relates to domestic appliances, and more particularly to washing machines.

An object of this invention is to provide a washing machine of an improved character in which flexible sheeting is used to wring the clothes by applied pressure, such as obtained by the application of a vacuum.

Another object of this invention is to provide a washing machine of the character having a flexible sheeting member for the wringing of clothes, in which means are provided for maintaining the sheeting member in proper position while the machine is being filled and/or is performing a washing operation.

Further objects and advantages of the present invention will be apparent from the following description, reference being had to the accompanying drawings wherein a preferred form of the present invention is clearly shown.

In the drawings:

Fig. 1 is a vertical cross-sectional diagrammatic view of a washing machine embodying features of my invention;

Fig. 2 is a vertical cross-sectional view of a modification;

Fig. 3 is a view similar to Fig. 2, but showing a further modification; and

Fig. 4 is a view similar to Figs. 2 and 3, but showing another modification.

A washing machine, embodying features of my invention, may include a substantially solid tub 10 having an opening 11 for introduction of articles to be washed, such as clothes or the like. A flexible sheeting bag 12, of rubber or the like, is provided in said tub 10. This bag may have an opening 13 adjacent the opening 11. Cover means 14 may be provided for said openings 11 and 13, and may take the form of a convexed disk 14, which is adapted to rest on the flange of opening 13. A pin 15 is placed in the opening 16 and is provided with a handle 17 and a cotter pin 18. The handle 17 may be used for the double purpose for lifting the cover 14 or for breaking the vacuum created within the bag 12 as hereinafter described.

Agitating means are provided for the articles to be washed. This may take the form of an oscillatable agitator 20 of conventional form. It may be provided with radial vanes 21, base 22, and an upstanding cylindrical extension 23. The base 22 and extension 23 may be perforated at 24 to allow the flow of water from or down to the opening 25, as hereinafter described. The agitator 20 is oscillated about a horizontal axis by a transmission 26 of any well known construction, which is caused to operate by the rotation of the pulley 27. A solenoid controller 26a is provided, which causes the agitator 20 to oscillate or remain idle, depending on the energization or deenergization of solenoid 26a.

The bag 12 is provided with another opening 28 at the bottom. The rim of this opening is

2

secured between the bottom 29 of the tub 10 and the disk 30, which is secured to the bottom 29 by means of the bolts 31. The transmission 26 is secured in an air-tight and water-tight manner to the bottom 29. An oscillatable shaft 32 extends from the transmission 26 and is secured to the agitator 20. The shaft 32, near the place where it emerges from the transmission 26 may be provided with a seal capable of withstanding upward air pressure or downward water pressure, to prevent any substantial flow of either air or water along said shaft 32.

Means are provided selectively to apply a vacuum to the space 33, between said sheeting 12 and tub 10, and to the space 34, within said sheeting bag 12. This may take the form of connecting means or pipes 35, 36 and 37, which lead to the vacuum pump 38, which discharges through the pipe 39, trap 40 and discharge pipe 41. The vacuum pump 38 is provided with a pulley 42. The pulleys 27 and 42 are connected by belts 43 and 44 with pulleys 45 on the motor 46.

Valve means are provided for controlling the application of vacuum to the spaces 33 and 34. Thus a solenoid valve 47 is placed in pipe 35, and a solenoid valve 48 is placed in the branch 49 leading from the pipe 36. The solenoid valve 47 is also provided with a pipe 50 which may be connected to the pipe 35, on the tub side of the valve 47, when it is desired to break the vacuum in space 33. The pipe 50 is open to the atmosphere, and the valve 47 is a two-way valve capable of connecting the pipe 35 either with the pipe 50 or the portion 35a which leads to the branch 37. By this construction the valves 47 and 48 control the selective application of a vacuum to the spaces 33 and 34. In addition, the pipe 50 is connected to 35 and space 33 to break the vacuum in space 33 at the same time a vacuum is applied to the space 34.

Water supply connecting means connectible to a source of water supply is provided, for the purpose of supplying water to the space 34. This may take the form of a pipe 51, which is connected to the pipe 36 at one end, and to a thermostatic solenoid valve 52 at the other end. The valve 52 is connectible to a hot water supply pipe 53 and a cold water supply pipe 54. A solenoid structure 55 opens the valve 52 to supply either hot water alone or a thermostatically controlled mixture of hot and cold water or cold water alone from the pipes 53 and 54 to the pipe 51. The construction valve 52 and 55 is well known and is therefore not further described.

A timer 56 is provided for controlling the operation of the motor 46, transmission control 26a, agitator 20, pump 38 and valves 47, 48 and 52. The timer 56 may be connected to a source of electrical supply 57, and is connected by lines 58 within a cable 58 with the motor, controller and valves, as indicated. The timer 56 may be pro-

vided with a synchronous motor which rotates and opens and closes proper contacts to send electrical energy to the controlled devices in the proper sequences. The construction of the timer 56 is well known and is therefore not further described.

Means are provided for preventing the breaking of the vacuum in the pump 38. To this end, a pipe 59 leads from the bottom of trap 40 to the pipe 37. This pipe is of very small bore, and allows but a small amount of liquid to flow through it, compared to the total capacity of pump 38. A screen 60 is provided in the trap 40. The trap 40 maintains a constant supply of liquid below the level of pipes 39 and 41, and this liquid is recirculated through the pipes 39 and 59, and thus keeps the pump primed whenever there is no liquid coming from the pipe 36.

The tub 10 is provided with bulges 60 to allow the flow of air to the pipe 35 at its connection 61 with the tub 10.

A water level switch is provided. This includes a hinged lever 63, between the tub 10 and bag 12, which actuates a switch within timer 56. The switch controls solenoid structure 55, in series with the timer-controlled switches. When the lever 63 is pressed outwardly by the rise in water level in bag 12, the flow of water through valve 52 stops.

In the operation of the structure shown in Fig. 1, the cover 14 is removed, and clothes and detergent are placed in the space 34 and the cover 14 is then placed over the opening 13. The timer 56 is then actuated by the handle 62 to start its operation. It then sequentially sends the proper electrical current through the cable 58. First it sends current to the motor 46, valve 47 and to the solenoid 55 to cause a vacuum to be created within space 33, and to cause hot water to be introduced by the pipe 53 past the valve 52, through pipes 51 and 36 into the space 34. Water continues to flow into the space 34 until the level of the water reaches the level of timer 56. The outward pressure of water on the bag 12 causes the bag to deflect the lever 63 outwardly. This lever opens the said switch within the timer 56, which opens the lines to the solenoid 55, thus stopping the introduction of water into the space 34. Thereafter the timer 56 opens the solenoid timer switches and disconnects the lines to solenoid 55, and connects the lines to transmission controller 26a, to cause oscillation of agitator 20. During the time that the clothes and water were being introduced into the space 34, the motor 46 was rotated to cause operation of the pump 38, and to maintain the valve 47 open, while the valve 48 was closed in such a manner as to cause the pump 38 to impart a vacuum to the space 33. This held the bag 12 distended against the tub 10 and maintained the space 34 fully opened. However, at the end of the agitation period, the timer 56 actuates the valve 47 to connect the space 33 with the pipe 50, actuates the valve 48 to open it, and deenergizes the controller 26a. This connects the pump 38 with the space 34, stops the agitator 20, and breaks the vacuum in space 33. The pump 38 withdraws liquid from the space 34 and eventually imparts a strong vacuum to this space. The atmospheric pressure then prevailing in the space 33 causes the bag 12 to collapse and press against the clothes, to wring the same and expel all free water, which drains through the openings 24, and around the agitator, to the opening 25, through the pipes 36, 37 and pump

38 eventually to be discharged at 41. The operation is then repeated automatically one or more times with hot or tepid water, or cold water, to provide one or more rinses of the clothes.

5 A previously applied vacuum in the space 33 is automatically reduced while a vacuum is being applied to the space 34. This is accomplished by connecting the atmosphere through pipe 50, two-way valve 47 and pipe 35 to the space 33 to reduce the previously applied vacuum while a vacuum is being applied to the space 34 through pipes 36, 49, valve 48, pipe 37 and vacuum pump 38. Conversely, a previously applied vacuum in the space 34 (applied at the end of the first wash agitation period) is automatically reduced while a vacuum is being applied to the space 33. This is accomplished by introducing rinse water under pressure from either or both the pipes 53 and 54 into the space 34 while a vacuum is being applied to the space 33. The introduction of the rinse water into space 34 thus automatically reduces the vacuum in space 34 (which was previously applied at the end of the first agitation period) while a vacuum is being applied to the space 33. Thus a vacuum from pump 38 is selectively applied to either of the spaces 33 and 34 and means are provided selectively to reduce the vacuum in the other of said spaces while a vacuum is applied to either of said spaces.

30 It is to be understood that, if desired, a pump may be connected to the space 33 with both the suction and discharge connected by solenoid valves and pipes to the space 33 and to the atmosphere. The pump may be operated to impart a vacuum to space 33 while the tub is being filled with clothes and water and while the agitator oscillates. Thereafter pressure may be imparted to the space 33 by the discharge from the pump. If desired liquid in lieu of air may be so pumped to the space 33.

35 In the modification shown in Fig. 2, a tub 70 is provided with an agitator 71, substantially as in Fig. 1. However, in this case the tub 70 is provided with an opening 73 which is outwardly flanged as indicated. A cover 74 is hinged at 75. It carries a flexible sheeting bag 76, which is vulcanized or otherwise secured to the flange 77 of the cover 74. Tension springs 78 are provided to maintain the bag 76 upwardly while agitation is taking place. An opening 79 is provided to maintain atmospheric pressure within the space 80. A pipe 81 is connected to a vacuum pump 82, which discharges through pipe 83. The opening 84 is provided in the tub 70 for the breaking of the vacuum in space 85. The opening 84 is covered by a hinged cover 86 which may be opened by pulling the handle 87. It is to be understood that the transmission 72, pump 82, and the pipe 81 may be connected to structures similar to those disclosed in Fig. 1, and that the same may be controlled by a timer. On the other hand, the transmission 72 and pump 82 may be driven from a single motor by any form of transmission which is capable of selectively operating the transmission 72 and pump 82.

60 In the operation of the device shown in Fig. 2, the cover 74 is lifted by the handle 87 and clothes and water are placed in the space 85, together with detergent. The cover 87 is then lowered in place, and the transmission 72 is operated to cause oscillation of the agitator 71. Thereafter the agitator is stopped, and the vacuum pump 82 is started. The liquid is then withdrawn from the space 85, draining if necessary, through openings 88 in the agitator 71. After a certain length

of time, a vacuum is produced in space 85 of sufficient intensity to cause downward movement of the bag 76 in response to atmospheric pressure in space 80. This wrings the clothes and causes the water thus wrung from them to flow into the pipe 81 from whence it is discharged by the vacuum pump 82 through the pipe 83.

Instead of springs 78, the space 80 may be connected to the vacuum pump by a flexible pipe, the opening 79 being closed, in a manner similar to Fig. 1. The vacuum in space 80 is maintained while filling and washing and is broken while wringing.

In the modification shown in Fig. 3, the tub 90 is provided with an opening flange 91, an agitator 92 and a pipe 93. The agitator 92 and pipe 93 are to be connected to a transmission and vacuum pump substantially the same as in Fig. 1 or 2. A ring 94 carries a flexible sheeting bag 95, the periphery of which is adapted to cooperate with the flange 91. A vacuum breaking opening 96 is provided, which is opened and closed by the cover 97, hinged at 98. In the operation of this modification, the ring 94 and bag 95 are removed from the opening 91. Clothes, water and detergent are placed in the space 99. The ring 94 and bag 95 are placed on the opening 91. The agitator 72 is then operated for a desired length of time after which it is stopped. Thereafter a vacuum is applied at pipe 93. This withdraws the liquid in space 99 and thereafter causes a downward extension of the bag 95 against the clothes in the space 99 to wring them and remove the moisture therefrom.

In the modification shown in Fig. 4, the elements indicated by 90a through 99a are substantially identical with those shown in Fig. 3, with the exception that the agitator 92a is provided with an upwardly extended perforated post 100. The bag 95a is provided with an upstanding recess 101 which telescopes over the post 100, when the vacuum is applied, thus protecting the bag 95a against undue stretching when it impinges on the post 100. The operation of this modification is otherwise the same as described with regard to Fig. 3.

While the form of embodiment of the invention as herein disclosed, constitutes a preferred form, it is to be understood that other forms might be adopted, as may come within the scope of the claims which follow.

What is claimed is as follows:

1. In a washing machine, a substantially solid tub having an opening for introduction of articles to be washed, flexible sheeting in said tub having an opening adjacent said first named opening, cover means for said openings, agitating means for said articles to be washed, driving means for said agitating means, vacuum producing means, valve means selectively to connect the space between said sheeting and tub and the space within said sheeting to said vacuum producing means, said valve means including means to break the vacuum in the space between said sheeting and tub when a vacuum is applied to the space within said sheeting, and a timer controlling the operation of said driving means and valve means.

2. In a washing machine, a substantially solid tub having an opening for introduction of articles to be washed, flexible sheeting in said tub having an opening adjacent said first named opening, cover means for said openings, agitating means for said articles to be washed, driving means for said agitating means, a vacuum pump, connecting means from said pump to the space between said tub and sheeting, connecting means

from said pump to the space within said sheeting, valve means selectively to apply a vacuum from said pump through said connecting means to said space between said tub and sheeting and to said space within said sheeting, means to break the vacuum in the space between the tub and sheeting when a vacuum is applied to the space within said sheeting and a timer controlling the operation of said pump and valve means.

3. In a washing machine, a substantially solid tub having an opening for introduction of articles to be washed, flexible sheeting in said tub having an opening adjacent said first named opening, cover means for said openings, agitating means for said articles to be washed, driving means for said agitating means, a vacuum pump, connecting means from said pump to the space between said tub and sheeting, connecting means from said pump to the space within said sheeting, water supply connecting means connectible to a source of water supply to the space within said sheeting, valve means selectively to apply a vacuum from said pump through said connecting means to said space between said tub and sheeting and to said space within said sheeting, means to break the vacuum in the space between the tub and sheeting when a vacuum is applied to the space within said sheeting valve means controlling said water supply connecting means, and a timer controlling the operation of said pump and valve means.

4. In a washing machine, a substantially solid tub having an opening for introduction of articles to be washed, a flexible sheeting bag in said tub having an opening adjacent said first named opening, cover means for said openings, an agitator in said bag, a vacuum pump, means selectively to connect said pump to the space between said tub and bag and to the space within said bag, and means selectively to apply a vacuum from said pump to either of said spaces, means selectively to reduce the vacuum in the other said spaces while a vacuum from said pump is applied to either of said spaces.

5. In a washing machine, a substantially solid tub having an opening for introduction of articles to be washed, a flexible sheeting bag in said tub having an opening adjacent said first named opening, cover means for said openings, an agitator in said bag, a vacuum pump, connections from said pump to the space between said tub and bag and to the space within said bag and from a source of water supply to the space within said bag, valves in said connections selectively to apply a vacuum from said pump to either of said spaces, means selectively to reduce the vacuum in the other said spaces while a vacuum from said pump is applied to either of said spaces, a motor drivingly connected to said vacuum pump and agitator, and a timer controlling the operation of said motor and valves.
